Patented Feb. 18, 1919.

2 SHEETS—SHEET 2.

UNITED STATES PATENT OFFICE.

FRANCIS B. COCKBURN, OF CINCINNATI, OHIO, ASSIGNOR TO THE LODGE & SHIPLEY MACHINE TOOL COMPANY, OF CINCINNATI, OHIO, A CORPORATION OF OHIO.

ENGINE-LATHE-APRON OILING SYSTEM.

1,294,402.

Specification of Letters Patent. Patented Feb. 18, 1919.

Application filed July 2, 1917. Serial No. 178,226.

To all whom it may concern:

Be it known that I, FRANCIS B. COCKBURN, a citizen of the United States, and residing at Cincinnati, in the county of Hamilton and State of Ohio, have invented a new and useful Improvement in Engine-Lathe-Apron Oiling Systems, of which the following specification is a full disclosure.

My invention relates to an improvement 10 in the apron of an engine lathe.

An object of the invention is to provide an oil pumping and circulating system for lubricating the feed element bearings, operated by the feed mechanism. This requires 15 an apron structure differing radically from the conventional. Also, it is quite a problem to place the oil pump in the apron to be driven by the feed mechanism, in such a manner as not to disturb the requisite definite relative positions of the feed instrumentalities. For the leaf-type apron, I substitute a box-like structure comprising a base 20 oil container, an elevated gravity feeding oil chamber, a pump geared to the feed and 25 supplying the chamber from the container, and conduits to the feed bearings, draining into the container.

The features of the invention are more 30 fully set forth in the description of the accompanying drawings, forming a part of this specification, wherein:

Figure 1 is a front elevation of the carriage and apron, partly broken and in section, to more clearly show the details of 35 construction of the oil pump.

Fig. 2 is a top plan view of the apron and contained mechanism.

Fig. 3 is a section on line 3—3, Fig. 2.

Fig. 4 is a section on line 4—4, Fig. 2.

Fig. 5 is a section on line 5—5, Fig. 2.

Fig. 6 is a section on line 6—6, Fig. 2.

Fig. 7 is a detail section on line 7—7, Fig. 6.

Fig. 8 is a detail section on line 8—8, Fig. 6.

The invention is illustrated in connection with an engine lathe comprising the bed A, having the usual guide-ways B, upon which slides the carriage C, supporting the cross-feed tool-slide D. The bed is provided with the stationary rack E and the rotating lead screw F, and the apron frame G is secured to the under surface of the forward overhanging edge of the carriage.

The apron frame G comprises a floor 55 plate 1, a front wall 2 and a rear wall 3, the floor plate extending rearwardly beyond the rear wall and provided with a marginal upturned flange or lip 4, to form an oil well or container H. The front wall 60 2 is provided with an aperture 5 for convenient assembling and removal of the parts of the apron mechanism, and said aperture is closed by a cover plate 6 secured in place by bolts 7.

The apron mechanism may be of any specific type, that illustrated in the drawings being a type selected for the purposes of disclosure.

In general, this mechanism includes the 70 usual slidable sleeve 10 splined to the lead screw F and provided with opposing beveled pinions 12, 12, to be alternately intermeshed with a beveled gear 13, secured to a drive shaft 14, journaled in the rear frame wall 75 3 and in the cover plate 6. (see Fig. 6). A pinion 15 is secured to the shaft 14 and meshes with a constantly driven clutch member 16, (see Figs. 2 and 5), laterally shifted by suitable mechanism to alternately engage with either of two driven clutch members 17, 18, the member 17 being loosely journaled in the front cover plate 6 and provided with gear teeth 19, adapted to mesh with a pinion 20, on the tool-slide feed 80 screw 21, and the member 18 being secured to an intermediate transmission shaft 22, journaled in the sleeve of the member 16 and in a bearing 23 in the rear frame wall 3. The shaft 22 is provided with a pinion 24 meshing with a gear 25, which is keyed 85 to the carriage feed shaft 26, said shaft being journaled in the front cover plate 6 and rear wall 3, (see Fig. 4) and having secured to its rear end a pinion 27 meshing with 90 the stationary rack E. A hand feed shaft 28, (see Fig. 3) is journaled in the front and rear frame walls 2 and 3, and is provided with gear teeth 29, meshing with the gear 25 of the carriage feed shaft 26.

The upper surface, of the apron frame G, with its cover plate 6, is provided with a series of connecting oil pockets and grooves, forming, with the lower surface of the carriage, a gravity feed oil chamber, from which 105 suitable oil ducts and grooves distribute the oil to the various bearings of the apron mechanism, the surplus oil draining into the

oil-well H. From the well H, the oil is pumped up to the oil pockets or chambers, to maintain a constant circulation as long as the apron mechanism is in operation.

5 The oil chamber comprises a series of oil pockets 30, 31, 32, connected by intermediate oil grooves 33, 34, and an oil pocket 35 of the front cover plate 6, which is supplied from the pocket 30, through an oil groove 36 and 10 a conduit or spout 37. Two oil ducts 38, 39, lead downwardly and outwardly from the oil pocket 30 and supply oil to the front and rear bearings respectively of the hand feed shaft 28. A vertical oil duct 40 leads downward from the oil pocket 31, to convey oil to the rear bearing of the carriage feed shaft 26, and a vertical oil duct 41 leads downward from the oil pocket 35, of the front cover plate 6, to supply oil to the front bearing of 15 said shaft. In the same manner, vertical oil ducts 42 and 43 lead downwardly from the oil pocket 32 and the oil pocket 35, respectively, to supply oil to the rear and front bearings of the intermediate transmission 20 shaft 22, (see Fig. 5).

To supply oil to the bearings of the drive shaft 14, I provide vertical oil ducts 44, 45, leading downwardly from the oil pocket 35 of the cover plate 6 and from the oil pocket 30 32 of the apron frame, respectively, each terminating in oil grooves 46, 47, formed on the inner surfaces of the cover-plate 6 and frame wall 3, and leading to oil ducts 48, 49, in the front and rear bearings, respectively, of the drive shaft 14.

The oil pump comprises a body portion 60 secured to the front cover plate 6 and provided with reciprocating piston plunger 61, having a slotted head 62 for coöperation 40 with a driving stud 63, eccentrically mounted on a stud shaft 64. Secured to said stud shaft is a pinion 65 meshing with gear teeth 66 on the constantly driven clutch member 16, previously described, (see Figs. 1, 2, 4 45 and 5).

An intake ball valve 67 operates to permit oil to be drawn into the oil-chamber 68 during an upward suction stroke of the plunger 61 and to prevent the escape thereof through 50 the intake port 69, during a downward forcing stroke of said plunger. An exit ball valve 70 operates relative to the exit port 71, conversely to the ball valve 67 and a dis-

charge conduit 72, conveys the oil upwardly and discharges into the apron oil pocket 30. 55

The floor plate 1, of the apron frame, drains toward a central medial point at which I provide a drain-plug 73, to permit a withdrawal of the contents of the oil-well H. 60

Having described my invention, I claim:

1. In an engine lathe in combination with the bed and carriage mounted for travel on the bed, and a cross feed tool-holder on the carriage, an apron structure depending 65 from the carriage and provided with bearings, feed elements supported in the apron bearings and organized for moving the carriage on the bed and the slide on the carriage, said apron structure being also formed 70 to constitute a base oil container below the bearings, a relatively elevated gravity feeding oil chamber above the bearings communicating with the oil container, and oil conduits leading downwardly from the 75 chamber to the apron structure bearings, and thence draining into the base container, an oil pump controlling the passage from the container to the chamber, and a pump operating mechanism operatively connected 80 to the apron feed mechanism.

2. An apron structure as a housing for a feed mechanism, adapted for attachment to a lathe carriage, and comprising upper, floor and wall members, the floor and upper 85 members being formed respectively with a communicating base oil container and gravity feeding oil chamber, a pump controlling the oil circulation between said container and chamber, bearings for feed elements 90 positioned in the structure intermediate the container and chamber drawing into the container, and oil supplied through conduits leading from the chamber, said wall members being formed with provision for 95 assembling feed elements and a pump operating element in their respective bearings, and enabling automatic oil pumping, energized by the apron feeding mechanisms.

In witness whereof, I hereunto subscribe 100 my name, as attested by the two subscribing witnesses.

FRANCIS B. COCKBURN.
